PICTURE TELEGRAPH APPARATUS

Helmut Steiner, Berlin, Germany, assignor to
 C. Lorenz Aktiengesellschaft, Berlin-Tempelhof,
 Lorenzweg, Germany, a company

Application August 24, 1938, Serial No. 226,439
 In Germany August 24, 1937

3 Claims. (Cl. 178—13)

The present invention relates to improvements in or concerning picture telegraph apparatus.

Picture telegraph devices are known in which the writing system is moved in a direction perpendicular to the direction of advance of the record carrier, such as a sheet of paper, so that the record carrier may be an endless strip or tape. The writing or printing equipment of such picture telegraph apparatus is generally guided on bars and is operated by driving means so as to move this equipment along the fixed record carrier or paper. It is very important that the writing equipment is guided with utmost accuracy on the bars in order to exactly fix the distance between this writing equipment and the paper. The heretofore known devices of this kind suffer under the disadvantage that the position of the writing equipment relative to the record carrier or paper cannot be regulated during the recording process, so it is necessary in each case to stop the apparatus when such a regulation becomes necessary.

The invention has for its object to avoid this difficulty and accomplishes this by guiding the writing system on an eccentrically pivoted bar so that the position of the writing system relative to the record carrier can be changed during the recording operation by adjusting this eccentric member.

The invention will be more readily understood from the following description taken in conjunction with the accompanying drawing, the single figure of which is a perspective view of one embodiment according to the invention.

The record carrier or paper 1 is guided on a drum 2 and the writing system 3 is moved along said record carrier in a direction which is perpendicular to the direction in which the record carrier is advanced. The function means of the writing system may for instance be formed sim-

ilar to a loudspeaker system having a hammer-shaped writing member or stylus 4 which, however, for the sake of simplicity, has not been particularly shown in the drawing. The writing equipment is guided on two bars 5 and 6. The bar 5 is rigidly connected between the lateral supporting members 7 and 8, while the bar 6 is eccentrically pivoted in parallel relation to the bar 5. The writing system moves on the first bar by means of a sliding bearing 9 and is guided by the second bar by means of two pulleys 10. In cases that the position of the stylus 4 relative to the record carrier 1 is to be altered during the recording process, the bar 6 is moved eccentrically by the agency of a lever 11 so that the writing system is pivotally tilted about the axis of bar 5 so as to change its position with respect to the record carrier.

What is claimed is:

1. In a picture telegraph apparatus having a record carrier guided on a platten, a writing equipment, means for moving said equipment in a longitudinal direction perpendicular to the direction of the record carrier advancement, and means for guiding said writing equipment, which means comprise one fixed bar and a further bar which is eccentrically adjustable relative to said fixed bar.

2. In a picture telegraph apparatus as defined in claim 1, in which said fixed bar has a cylindrical cross sectional area, said writing system being tilted about the axis of said bar by means of said eccentric bar in order to vary the relative position between said writing system and said record carrier.

3. In a picture telegraph apparatus as defined in claim 1, in which said writing system is provided with pulleys adapted to guide said writing system on said eccentrically adjustable bar.

HELMUT STEINER.
